UNITED STATES PATENT OFFICE.

HARRY S. McCORMACK, OF NEW ROCHELLE, NEW YORK, ASSIGNOR TO UNDERWOOD TYPE-WRITER COMPANY, OF NEW YORK, N. Y., A CORPORATION OF NEW JERSEY.

TYPE-WRITING MACHINE.

No. 914,062.

Specification of Letters Patent. Patented March 2, 1909.

Application filed November 13, 1908. Serial No. 462,381.

To all whom it may concern:

Be it known that I, HARRY S. McCORMACK, a citizen of the United States, residing in New Rochelle, in the county of West Chester and State of New York, have invented certain new and useful Improvements in Type-Writing Machines, of which the following is a specification.

This invention relates to an improvement 10 in the sheet-adjusting plate disclosed in United States Patent No. 829,989, granted to me September 4, 1906.

The object of the invention is to improve 15 the construction of the plate with a view to making it practicable to register thereby a sheet whose leading edge is cut out for too great a part of the width of the sheet to permit it to be gaged readily by means of the device shown in said patent.

I provide upon the sheet-adjusting plate, 20 which is usually of a size to accommodate the entire width of the sheet, a gage between the front and back edges of the plate, but extending along only such portion thereof as 25 will make it convenient for gaging a cut-out sheet; said gage terminating short of one end or side of the main plate, to permit the uncut part of the leading edge of the sheet to project past the same. Provision may also be 30 made for gaging the leading edges of a sheet whose cut-out is too short to be registered by said gage.

Other features and advantages will hereinafter appear.

In the accompanying drawings, Figure 1 is 35 a perspective view of a platen and platen frame of an Underwood front strike writing machine, showing my improvements applied thereto, and showing a cut-out sheet as registered upon the adjusting or registering plate. Fig. 2 is a perspective view of the 40 registering plate, showing in dotted lines how a sheet provided with a shorter cut-out than as at Fig. 1, may be brought into register; and also showing how a sheet A having a wide or uncut leading edge may be registered. Fig. 3 is a diagram illustrating some different 45 lengths of cut-outs in the leading edges of the sheets. Fig. 4 is a sectional side elevation 50 illustrating a sheet carried around the platen and registered on the registering plate.

A platen 1, upon whose front side strike types 2, is journaled by an axle 3 in the ends 55 4 of a platen frame. Said ends are connect-

ed by a rod 5 running along the platen. A registering plate 6 is secured by screws 7 upon a pair of brackets 8, keyed to said rod 5 by keys 9 and adjustable along the platen. The screws 7 pass through slots 10 which 60 permit adjustment of the plate forwardly and backwardly, as usual. A sheet 11, whose leading edge 12 is cut away at 13 for the major portion of the width of the sheet, is laid upon the plate, and its cut-away edge 65 13 is set against a gage 14 extending from right to left along the main registering plate 6 at the rear portion thereof. The right hand edge of the sheet is set against a gage 15 formed upon the right hand end of the 70 main plate. The gage 14 is in the form of a strip or plate secured upon the rear portion of the main plate 6. At one end it may 75 abut against the side gage 15, while the other terminates short of the main plate 6, to permit the uncut portion 12 of the leading edge of the sheet to project back past the end of said gage or strip 14, as at Fig. 1. The front edge of the gage 14 is located between the front and rear edges of the main 80 plate 6, and preferably so far front that the edge 12 does not quite touch a ledge 16 which is turned up along the back edge of the main plate 6; the strip 14 being set back against said ledge.

A sheet 17, having in its leading edge a cut 85 away 18 shorter than the gage strip 14, may be adjusted in the manner seen at Fig. 2; the uncut portion 19 of its leading edge being set back against the gage 16 and resting partly upon the top of the gage strip 14; the gage or ledge 16 rising above said strip, as shown. The extreme right hand portion of the cut out 18 may be set back against a small gage 20 placed upon the top of the strip 14 at its 90 right hand end and fitted into the corner formed by the ledges 16 and 15. In adjusting the sheet 17, the plate 20 may be employed as a minor adjusting plate, the operator pressing down the leading edge 19 of the 100 sheet upon the said minor plate 14, and at the same time slipping the right hand corner of the sheet back against the gage 20 and carrying the sheet to the right until its side edge sets against the gage 15. The gage 20 105 is made small enough to fit in the smallest cut outs made in sheets, as at 21, Fig. 3; the leading edge 22 of this sheet 23 being set back against the gage 16 and being of sufficient length to enable the sheet to be regis- 110

tered properly without reference to the gage 20. It will thus be seen that there are three gages 20, 14 and 16, the gages 20 and 14 being of graduated lengths and superposed one upon the other and both upon the main registering plate 6, all the gages 20, 14 and 16 being parallel, although the gage 20 need have no length, as it is intended to support merely one point of the cut out in the sheet.

10 Having thus described my invention, I claim:

1. In a typewriting machine, the combination with a platen, of a sheet-registering plate mounted upon the delivery side thereof and provided at one end portion with a gage for the side edge of the sheet and having also a gage for the cut-out leading edge of a sheet, the last-mentioned gage arranged at the same end of the plate as said side gage and terminating short of the other end of the plate.

2. In a typewriting machine, the combination with a platen, of a sheet-registering plate mounted upon the delivery side thereof and having a ledge erected along its rear edge and provided at one end portion with a gage for the side edge of the sheet, and a gage secured upon said plate for the cut-out leading edge of a sheet, the last-mentioned gage placed forward of said ledge and terminating short of said plate at the end thereof opposite said side gage.

3. In a typewriting machine, the combination with a platen, of a main sheet-registering plate mounted upon the delivery side thereof and having a main gage erected along its rear edge, and a minor supplemental plate upon the rear portion of said main plate, said ledge rising above said supplemental plate, and the front edge of the supplemental plate serving as a gage for the cut-out leading edge of a sheet.

4. In a typewriting machine, the combination with a platen, of a main sheet-registering plate mounted upon the delivery side thereof and having a main gage erected along its rear edge, and a minor supplemental plate upon the rear portion of said main plate, said ledge rising above said supplemental plate, and the front edge of the supplemental plate serving as a gage for the cut-out leading edge of a sheet; said supplemental gage terminating between the ends of the main plate.

5. In a typewriting machine, the combination with a platen, of a main sheet-registering plate mounted upon the delivery side thereof and having a main gage erected along its rear edge, a minor supplemental plate upon the rear portion of said main plate, said ledge rising above said supplemental plate, and the front edge of the supplemental plate serving as a gage for the cut-out leading edge of a sheet, and a second

supplemental gage at one end of the said minor supplemental gage and rising above the latter to coöperate with the main gage to register a sheet having a relatively short cut-out.

6. In a typewriting machine, the combination with a platen, of a main sheet-registering plate mounted upon the delivery side thereof and having a main gage erected along its rear edge, a minor supplemental plate upon the rear portion of said main plate, said ledge rising above said supplemental plate, and the front edge of the supplemental plate serving as a gage for the cut-out leading edge of the sheet, a second supplemental gage at one end of the said minor supplemental gage and rising above the latter to coöperate with the main gage to register a sheet having a relatively short cut-out, and a gage upon said main plate for the side edge of the sheet.

7. In a typewriting machine, the combination with a platen, of a sheet-registering plate mounted upon the delivery side thereof and provided at its rear edge with an upturned ledge, a minor supplemental sheet-adjusting plate secured upon the rear portion of said plate at one end thereof and of less height than said ledge, the front edge of said minor plate serving as a gage for the leading edge of a cut-out sheet, a second gage secured upon one end of said minor plate to coöperate with said ledge to register a sheet having a cut-out too short to register against said minor plate, and a gage for the side edge of the sheet.

8. In a typewriting machine, the combination with a platen and a platen frame, of a registering plate lying along the top of the platen and provided with a series of gages to square the paper at the leading end.

9. In a typewriting machine, the combination with a platen, of a registering plate lying along the top of the platen and having gages at its rear and side edges to square the leading end and side edges of the paper, and a series of supplemental gages for the leading end of the paper.

10. In a typewriting machine, means for registering the paper at its leading end, comprising a main plate extending along the top of the platen and having a gage at its rear edge, and a series of supplemental gages of graduated lengths parallel with said gage, but slightly forward thereof, said supplemental gages in the form of superposed strips extending along the top of the main plate, but less than the entire length thereof.

HARRY S. McCORMACK.
